United States Patent Office

Des. 224,582
Patented Aug. 8, 1972

224,582

JACKET

Louis J. Fagioli, 120 Faywood Ave.,
Boston, Mass. 02128

Filed Jan. 4, 1971, Ser. No. 103,960

Term of patent 14 years

Int. Cl. D2—02

U.S. Cl. D2—183

FIG. 1

FIG. 2

FIG. 1 is a side perspective view of a jacket showing my new design; and

FIG. 2 is a perspective view thereof taken from the other side, the back being plain and conventional.

I claim:

The ornamental design for a jacket, as shown.
